UNITED STATES PATENT OFFICE.

ANNIE SHORTLE, OF ST. JOSEPH, MISSOURI.

DESIGN FOR A MOTHER'S NURSING-DRESS WAIST.

44,594.

Specification for Design.

Patented Aug. 26, 1913.

Application filed February 21, 1913. Serial No. 750,010. Term of patent 7 years.

To all whom it may concern:

Be it known that I, ANNIE SHORTLE, a citizen of the United States, residing at the city of St. Joseph, in the county of Buchanan and State of Missouri, have invented a new, original, and ornamental Design for a Mother's Nursing-Dress Waist, of which the following is a specification, reference being had to the accompanying drawing, forming a part thereof.

The figure is a front view of a mother's nursing dress waist showing my new design.

I claim:

The ornamental design for a mother's nursing dress waist, as shown.

ANNIE SHORTLE.
